DESIGN FOR A COMBINED COFFEEPOT, CREAM PITCHER, AND SUGAR CON- TAINER

Emil A. Schuelke, Meriden, Conn., assignor to
The Napier Company, Meriden, Conn., a cor-
poration

Application September 14, 1934, Serial No. 53,285

Term of patent 14 years

To all whom it may concern:

Be it known that I, EMIL A. SCHUELKE, a citizen of the United States, residing at Meriden, in the county of New Haven and State of Connecticut, have invented a new, original, and ornamental Design for a Combined Coffeepot, Cream Pitcher, and Sugar Container, of which the following is a specification, reference being had to the accompanying drawing, forming part thereof.

Fig. 1 is a perspective view of a combined cof-

feepot, cream pitcher, and sugar container showing my new design;

Fig. 2 is a front view of the same; and

Fig. 3 is a side view of the same.

I claim:

The ornamental design for a combined coffee-pot, cream pitcher, and sugar container substantially as shown.

EMIL A. SCHUELKE.
